UNITED STATES PATENT OFFICE.

ANDREW CLAUDE TYSON, OF KISSIMMEE, FLORIDA.

BILLIARD-CUE LOCK.

1,342,517.

Specification of Letters Patent.

Patented June 8, 1920.

Application filed December 20, 1919. Serial No. 346,241.

To all whom it may concern:

Be it known that I, ANDREW CLAUDE TYSON, a citizen of the United States, residing at Kissimmee, in the county of Osceola and

5 State of Florida, have invented a new and useful Billiard-Cue Lock, of which the following is a specification.

This invention relates to an improved cue lock, adapted for use in connection with 10 racks for holding cues for playing billiards and pool, the object thereof being to securely retain the cues in position against unauthorized use, and to permit the removal thereof only by means of a key, thus serving as a safe keeping for cues of individual 15 players.

A further object of the invention is to provide a locking device adapted for application to racks of known type, without alteration of the construction of the rack, and provided with means for locking the same in closed positions so as to permit the same to be opened, only by one possessing the necessary key.

25 With the above and other objects in view which will appear as the description proceeds, the invention resides in the combination and arrangement of parts and in the details of construction hereinafter described 30 and claimed, it being understood that within the scope of what is claimed, changes in the precise embodiment of the invention shown can be made without departing from the spirit of the invention.

35 In the accompanying drawings:

Figure 1 is a front elevation of a rack provided with my improved cue lock;

Fig. 2 is a horizontal sectional view, and showing the hinged sections of the locking 40 device swung outwardly in dotted lines, the section being taken on the line 2—2 of Fig. 1 and with a portion of one member broken away at its lock, and

Fig. 3 is a vertical sectional view taken 45 on the line 3—3 of Fig. 2.

Referring to the drawings in detail, in which like reference characters designate corresponding parts throughout the several views, the numeral 10 indicates a rack of 50 known or any preferred construction for supporting a series of cues 11 for playing billiards or pool. As indicated, this rack includes the base portion 12 of the usual flanged type provided with sockets for receiving the handle or large ends of the cues, while the upper portion thereof is provided

with a top section 13 provided with openings for receiving the tip ends of the cues therethrough. The rack may be provided with the usual backing, which includes vertical 60 end members 14 connected by the upper and lower cross members described.

The locking device includes an elongated body member 15 which is disposed parallel to the top and bottom members 13 and 12 65 and between the same, the ends of the body member 15 being recessed or rabbeted as shown at 16, to receive the end members 14 therein, in order that the inner face of the body member 15 will lie flush with the inner 70 faces of the end members 14 while the outer face of the body member 15 will be disposed forwardly of the outer faces of the end members 14 as clearly shown in Fig. 2 of the drawings.

75 The body member thus extends across the cue rack and has hinged to the ends thereof, as indicated at 17, the hinged locking members or sections 18, which are each one half the length of the body member so as to 80 come together at their inner ends intermediate of the length of the body member as indicated at 19, thus forming one continuous barrier at the front of the body member with the ends abutting and disposed 85 in co-extensive relation.

The forward face of the body member and the rear face of the members or sections 18 are each provided with semi-circular recesses disposed in registration, to provide 90 circular openings 20 for receiving the cues 11 therethrough. When the hinged members or sections 18 are in the positions stated, they are held secured in locking position by locking members 21 mounted near the ends 95 of the members 18 and co-acting with suitable keepers 22 carried by the body 15, the same being snap locks which are key operated as of the type provided with sliding tumblers common in the well known 100 Yale or Harvard locks. By locking each section in the manner stated, the cues are prevented from being removed and thus the cues of the particular players are protected from use by any other than the person 105 reserving them. Obviously, the lock may be opened by anyone possessing the necessary key, in order to obtain access to and remove the cues as desired. The device will not interfere with the convenient application and removal of the cues as ordinarily possible when the hinged sections or mem-

bers 18 of the locking device, are swung to open positions, in the direction indicated in Fig. 2, it being understood that said sections may be swung outwardly against the 5 wall or support to which the device or rack is applied. It is also to be understood that the ends of the body 15 are secured to the end members 14, through the medium of screws or like fastening means 23 so as to hold the device in place. In addition, when the hinged members are closed in locking 10 relation, the screws are entirely hidden from view and are inaccessible, thereby preventing the same from being detached from the 15 back.

By mounting the locking device as a barrier across the rack and receiving or engaging the intermediate portions of the cues, it will be seen that it will be impossible to lift 20 the handle ends of the cues from their sockets in the base member 12 and removing the same by dropping their tip portions from the top member 13 of the rack, unless the hinged sections of the locking device are 25 unlocked and swung outwardly. Since access to the rack by a proper key, by one authorized to remove the cues, unauthorized use of the cues is prevented whereby individual players may be guaranteed the sole 30 use of the cues.

Having thus described the invention what I claim is:

1. A billiard cue locking device for cue racks, comprising a body member having 35 means for securing the same to the rack, said body member having semi-circular recesses in its front face, keepers carried by said body member, hinged sections mounted

at the ends of the body member, and being adapted to be brought into abutting relation at their inner ends when closed against the body member, said hinge member having recesses corresponding to the first mentioned recesses and adapted to register therewith when the hinged members are closed 45 against the body member, and key operated locking devices carried by the free end portions of the hinged sections coöperating with said keepers to secure the hinge members against said body member, whereby to retain the cues in position. 50

2. A locking device for cue racks provided with a body member having cue receiving sockets and a top member having apertures receiving the cue tips therethrough, and end members connecting said top and bottom members, an elongated body member having its end portions recessed and secured to said end members, sections hinged at their outer ends to the ends of the body member, securing means for the body member at the end thereof adapted to be concealed by said hinged section when closed against the body member, locking devices for securing the free ends of the hinged section against the 60 body member, and said body member and hinged sections being provided with coacting recesses for receiving cues. 65

In testimony that I claim the foregoing as my own, I have hereto affixed my signature 70 in the presence of two witnesses.

ANDREW CLAUDE TYSON.
